ARTICLE FORMING APPARATUS

Eugene A. Kruse, Downers Grove, Ill., assignor to Western Electric Company, Incorporated, New York, N. Y., a corporation of New York

Application December 20, 1943, Serial No. 515,031

6 Claims. (Cl. 78—18)

1

This invention relates to article forming apparatus and more particularly to apparatus for forming a head on a fine wire to adapt it for attachment to a piezoelectric crystal.

In the manufacture of piezoelectric crystals for use as frequency control devices in the electrical communication apparatus, the wires which also serve as a support for the crystals are attached to a flat surface of the crystal, usually adjacent the center of the surface from which the lead wires extend at right angles. In order to facilitate the attachment of the lead wires to the crystal and to make it less probable that the lead wires will be loosened from the crystals, a flattened enlargement or head may be formed on the lead wire. Due to the thinness of the wire, considerable difficulties have been encountered in forming a head on it.

It is an object of the present invention to provide a simple and effective device for forming headed articles.

In accordance with one embodiment of the invention, there is provided a feed mechanism for feeding a wire into position between a pair of clamping jaws and against a movable abutment which determines the amount of wire extending beyond the clamping jaws. The movable abutment is mounted upon a die supporting member having dies thereon adapted to engage and form the portion of the wire extending beyond the clamping jaws in cooperation with forming surfaces cut into the clamping jaws. The two clamping jaws, which also serve as a die, are movable eccentrically of the wire to cooperate with shearing jaws for shearing the headed section of wire from the body of the wire. Thus the chief function of the clamping jaws is to serve as a shearing and forming die for shearing and forming the wire.

A complete understanding of the invention may be had by reference to the following detailed description when considered in conjunction with the accompanying drawings, wherein

Fig. 1 is a side elevational view of an apparatus embodying the invention, parts being broken away to show features of construction of the means for supporting the dies and of the clamping and wire-feeding connecting mechanisms;

Fig. 2 is a view taken substantially along the line 2—2 of Fig. 1 in the direction of the arrows, part being shown in section and part in front elevation;

Figs. 3, 4, 5 and 6 are fragmentary horizontal sectional views taken in the direction of the arrows substantially along the line 3—3, 4—4, 5—5 and 6—6, respectively, as indicated in Figs. 1 and 2;

Figs. 7, 8, 9 and 10 are enlarged fragmentary sectional views taken through the various forming dies and the movable abutment, Fig. 7 showing

2

the wire extending a predetermined distance beyond the clamping jaws and engaging the movable abutment, Fig. 8 showing the clamping jaws moved to the position where they have cut off a length of wire from the main body thereof and also showing the first of the forming dies which operate on the end of the wire in the steps of forming the head thereon, Fig. 9 showing the second forming die, and Fig. 10 showing the final forming die.

In the drawing as shown, particularly in Fig. 1, a wire 15, which may be drawn from any suitable supply thereof, is fed through a guide tube 16, suitably mounted on a base member 17. The guide tube 16 serves to direct the wire 15 from the substantially horizontal plane into a substantially vertical plane and the tube is fixed on the base member 17 by means of a suitable support block 18. Positioned directly above the upper vertically extending portion of the guide tube 16 is a guide sleeve 19 mounted in a feed sleeve 20. The feed sleeve 20 is freely slideable within a tubular bushing 21, which is threaded on its outer surface for adjustably positioning it in a block 22, in turn suspended from the underside of a main cross plate 23, for example, by means of screws 24—24. The block 22 has a guide pin 25 threaded into it which extends through and bears in an aperture 26 of a feed lever 27. The feed lever 27 is suitably fixed to the feed sleeve 20 and has suspended from its lower side a bracket 28, on which a wire clamping lever 29 is pivoted by means of a pivot pin 30. The upper end of the tubular bushing 21 serves as a shoulder against which a cooperating shoulder 31 formed on the upper end of the feed sleeve 20 will normally rest.

The lower end of the guide sleeve 19 and feed sleeve 20 are cut away adjacent their lower ends to provide a shoulder 32, against which the wire 15 may be pinched or pressed when the lever 29 is rocked clockwise about the pivot pin 30. Thus, the wire 15 may be gripped between the right hand end of the lever 29 and the shoulder 32 and may be moved upwardly with the levers 29 and 27, which will be guided by the guide pin 25 and the inner surface of the bushing 21 to feed a length of wire 15 upwardly.

The main cross plate 23 is mounted in spaced relation with respect to the base member 17 by means of a pair of cross plate supporting walls 40 and 41, on which the plate 23 may be adjustably fixed by set screws 42, 43, 44 and 45, which may be adjusted to bear against the outer surfaces of the side walls 40 and 41 (Fig. 6). Cooperating with the set screws 42 to 45 are a pair of set screws 46 and 47, which cooperate with a locating screw 48 to adjust the main cross plate 23 toward the front or rear of the mechanism. The set screws 46 and 47 bear against the front edge of the walls 40 and 41 and the adjusting

screw 48 is threaded in a T-head nut 49 set into a T-slot 50 in the plate 23. The adjusting screw 48 is freely rotatable in an aperture 51 formed in a main standard 52, which is suitably attached to side walls 40 and 41 and the head of the adjusting screw 48 bears against a shoulder 53 formed in the aperture 51. By properly manipulating the said screws 46 and 47 and the adjusting screw 48, the plate 23 may be adjusted toward the rear or front of the apparatus and after being properly located, the adjustment screw 48 may be locked in the desired position by means of a set screw 54 (Fig. 6). Each of the set screws 42, 43, 44, 45, 46 and 47 is provided with lock nuts 55, whereby, after the set screws have been properly adjusted to position the plate 23 in the desired location, the set screws may be locked against accidental displacement of the plate.

Formed in the plate 23 is a shouldered aperture 60, which is adapted to receive a tubular bushing 61, which is provided with an annular shoulder 62 adapted to engage the shoulder in the aperture 60 to be supported thereby. The bushing 61, in turn, has a shouldered aperture formed in it in which there are positioned a pair of semi-cylindrical guiding members 63 and 64. These guiding members 63 and 64 are provided with shoulders which cooperate with the shoulders in the bushing 61. The semi-cylindrical guiding member 64 has an aperture 65 formed in it (Fig. 2) for receiving a gripping member 66, which is urged toward the guiding member 63 by a pin 67 positioned in a bearing aperture 68 formed in the plate 23. The pin 67 is freely slideable in the aperture 68 and has a head portion 69 having springs 70 and 71 disposed on opposite sides of it, the spring 70 encircling the shank of the pin and being effective to urge the pin to the right (Fig. 2). The two springs 70 and 71 are positioned in an enlarged portion of the aperture 68 and the spring 71 may be forced to the left by a cam-actuated plunger 72 under the action of a cam 73 (Figs. 2 and 6).

A pivot stud 75 (Figs. 1 and 6) is threaded into the main cross plate 23 and serves as a pivot about which a pair of cooperating clamping members 76 and 77 may be rocked. The clamping member 76 is slightly longer than the clamping member 77 and has a projection 78 formed thereon which extends over the forward end of the clamping member 77 and carries its right end surface normally in substantial alignment with the right hand surface (Fig. 6) of the clamping member 77. A compression spring 79 seated in sockets 80 and 81 formed in the clamping members 76 and 77, respectively, normally urges the forwardly extending ends of the clamping members apart to permit the end of the wire 15 to be fed into position between the two clamping members. The pivot stud 75 holds the clamping members 76 and 77 in a position where substantially semi-circular depressions 82 and 83, respectively (Figs. 7 and 8), formed therein may clamp a wire which has been fed upwardly between the guiding members 63 and 64 when the clamping members 76 and 77 are in their normal position, as shown in Fig. 7. The wire 15 will be clamped by the clamping members 76 and 77 and will be held by them when the forward ends of the clamping members are forced together against the action of the spring 79 and if the wire is fed upwardly between the clamping members, it will be held in the depressions 82 and 83, which taper outwardly, as shown at 84 and 85, to form a die

into which the end of the wire 15 will be pressed, as will be explained hereinafter.

The forward ends of the clamping members 76 and 77 extend between a pair of upwardly extending blocks 86 and 87, which extend upwardly from the main cross plate 23. Threaded into the block 86 is an adjustable abutment screw 88, which serves as a fixed abutment against which the clamping member 76 will be stopped when it is moved clockwise about pivot stud 75. The adjustable abutment screw 88 may be locked in place by means of a lock nut 89 after it has been set in its proper position. Also seated in the block 86 is a plunger 90, normally urged to the right (Fig. 6) by a compression spring 91 entering a cylindrical pocket 92 formed in the plunger 90 and abutting the end of a socket 93, which is formed in the block 86 and is adapted to receive and slidably position the plunger 90. The block 87 has a pair of abutment screws 94 and 95 threaded into it and locked in position by lock nuts 96 and 97. These abutment screws 94 and 95 are adapted to prevent counter-clockwise movement of the clamping members 77 and 76 (Fig. 6) beyond a predetermined position to which the clamping members will be urged by the combined action of the springs 91 and 79, the spring 91 urging the clamping member 76 to rock counter-clockwise to carry its projection 78 into engagement with the abutment screw 95 and the spring 79 urging the clamping member 77 into engagement with the abutment screw 94. Slidably positioned in the block 87 is an actuating pin 98 adapted to engage the clamping member 77 and move it clockwise (Fig. 6) when the actuating pin 98 is forced to the left (Fig. 6) by a cam member 99 formed integrally with the cam 73. The cam member 99 and cam 73 are provided with a handle 100, whereby they may be actuated and the cam member 99 and cam 73 are pivoted for rotation about a pivot screw 101 threaded into the main cross plate 23. From the foregoing, it will be apparent that the clamping members 76 and 77 function primarily as a shearing and forming die.

The standard 52 is provided with a forwardly extending portion 110, in which there is rotatable a bearing sleeve 111 provided with a lower shouldered portion 112 and threaded at its upper end to receive a retainer ring 113, which cooperates with the shoulder 112 to hold the sleeve 111 in the forwardly extending portion 110 of the standard 52. The shouldered portion 112, as seen most clearly in Fig. 4, is provided with a series of sockets 114, 115, 116 and 117 adapted to receive a spring-pressed plunger 118 slideable in an aperture 119 formed in the standard 52. The plunger 118 has a reduced portion 120, which is encircled by a compression spring 121 positioned between the larger portion of the plunger 118 and a plug 122 threaded into the rear end of the aperture 119. Thus the plunger 118 is normally urged toward the front of the apparatus and into one of the sockets 114, 115, 116 or 117. The plunger 118 is bifurcated at its rear end to receive an operating lever 123, which is provided with a slot 124 for receiving a pin 125. The end of the lever 123 is pivoted at 126 on a bracket 127 suitably attached to the standard 52, for example, by means of machine screws 128-128. By means of the just described mechanism, the plunger 118 may be retracted to permit the partial rotation of the sleeve 111, as will be described hereinafter, whereby the plunger 118 may be entered in any one of the sockets 114 to 117, inclusive. Extend-

ing downwardly from the extending portion 110 of the standard 52 are a pair of plates 130 and 131 adapted to receive set screws 132 and 133 in positions to abut surfaces 134 and 135 of the shoulder 112, thereby to limit the amount of rotation of the shoulder with respect to the forwardly extending portion 110 of the standard 52. The set screws 132 and 133 may be locked in place after they have been adjusted by means of lock nuts 136-136.

Slidably vertically in the sleeve 111 is a shaft or rod 140, to which there is attached a guide block 141 (Figs. 1 and 3). The guide block 141 is fixed to the rod 140 by means of a machine screw 142 and cooperates with surfaces 143 and 144 (Fig. 3) formed on an upwardly extending semi-cylindrical portion 145 of the sleeve 111, thereby to prevent rotation of the rod 140 with respect to the sleeve 111 while permitting vertical reciprocation of the rod with respect to the sleeve. By means of this construction, the rod 140 may be rotated through arcs as determined by the position of the set screws 132 and 133 with respect to the surfaces 134 and 135 on the shoulder 112 and will carry the sleeve 111 with the rod in its partial rotations but the rod 140 may be reciprocated with respect to the sleeve 111.

At its lower end, the rod 140 has an enlargement or block 146 formed on it (Figs. 1, 2 and 5) which constitutes a die supporting block provided with sockets 147, 148, 149 and 150 adapted to receive a gage member 151 and forming dies 152, 153 and 154, respectively. The gage member 151 and forming dies 152, 153 and 154 may be secured in the block 146 by means of set screws 155-155, which will serve to position the gage member or end-forming dies in the desired position, where they may be aligned with the end of the wire 15 by manipulating a handle 156 fixed to the block 146.

The upper end of the rod 140 has a socket 160 formed in it for receiving a reduced portion 161 of a connector member 162. The reduced portion 161 of the connector member 162 has an annular groove 163 formed in it into which pins 164-164 may project. The pins 164 may be driven into apertures 165 formed in the rod 140 and will thus permit rotation of the connector member 162 with respect to the rod 140 while preventing relative vertical movement between them. The upper end of the connector member 162 has a slot 166 formed in it for receiving a lever 167, which may be pivotally attached to the connector member 162 by a pin 168 fixed in the connector member 162 and engaging a slotted aperture 169 in the lever 167. The lever 167 is pivoted on a pivot pin 170 fixed in a bracket 171, which is, in turn, supported on the upper surface of the standard 52, being secured thereto by means of machine screws 172. The left end of the lever 167, as shown in Fig. 1, has a contractile spring 173 attached to it and attached to the portion 110 of the standard 52, whereby the lever 167 is normally urged to rock counter-clockwise about the pivot pin 170. Rotatably mounted in the bracket 171 is a shaft 174 having a crank handle 175 secured to one end of it (Fig. 2) and having a cam 176 secured to it in alignment with a cam member 177 fixed on the lever 167.

From the foregoing, it will be apparent that when the shaft 174 is rotated clockwise, as shown in Fig. 1, the cam 176 will engage the cam member 177 and rock the lever 167 clockwise about the pivot pin 170 until the widest portion of the cam 176 moves out from under the cam member

177, whereupon the spring 173 will snap the lever 167 back to the position shown, thus to drive the rod 140 rapidly downward. In order to adjust the effect of the spring 173, a weight 178 may be attached to the lever 167 in any desired position on that portion of the lever extending to the right (Fig. 1) of the pivot pin 170 and in this manner the percussive stroke of the rod 140 may be controlled. Correspondingly, the effect of the dies on the end of the wire 15 may be controlled by adjusting the position of the weight 178.

By reference to Figs. 7, 8, 9 and 10, it will be seen that the gage member 151 is cut away at its lower end so that when the gage member is positioned over the wire 15, the wire may be fed upwardly into engagement with a surface 179 of the gage member while surface 180 of the gage member is engaging the top of the clamping member 77 and in this manner the feeding of more than a predetermined amount of wire 15 above the surface of the clamping member will be prevented. The configuration of the forming die 152 is shown at 181 in Fig. 8. This is the first die to be used after the gage member has served as an abutment against which the wire 15 is fed and the die aperture 81 performs the first forming step on the end of the wire. Figs. 9 and 10 show the second and third forming dies 153 and 154, which have the configuration illustrated at 182 and 183, respectively.

A more complete understanding of the invention may be had from the following brief description of the mode of operation thereof. A strand of wire withdrawn from any suitable supply may be entered in the guide tube 16 and fed upwardly through the guide sleeve 19 either by means of the wire-clamping lever 29 or by simply forcing the wire through the tube 16 when the machine is being prepared for operation. After the wire has been fed up through the guide sleeves 19 and through the semi-cylindrical guiding members 63 and 64, the block 146 may be swung to position to align the gage member 151 with the upper end of the wire 15 and then by proper manipulation of the feed lever 27 and wire-clamping lever 29, the wire may be advanced to engagement with the surface 179 of the gage member 151. It, of course, is assumed that prior to feeding the wire 15 into engagement with the gage member, the block 146 had been shifted by means of the handle 156 to position the gage member over the guide tubes and that the plunger 118 had entered the socket 117, thus to accurately align the gage member with the upper end of the wire. After the wire has thus been properly positioned to be operated upon by the forming dies, the first forming die 152 may be shifted into alignment with the wire. Before the die 152 is driven down to form the end of the wire, the lever 100 should be manipulated to force the actuating pin 98 (Fig. 6) to the left. When the lever 100 is moved clockwise, cam 73 will be effective before cam member 99 and the wire will be clamped by the gripping member 66, thus to facilitate the shearing of a short length of wire from the supply thereof. The cam 73 is thus formed to aid in the shearing operation and also to hold the wire while the guide sleeve 19 and feed lever 27 are moved down to grip and feed another length of wire.

When the actuating pin 98 is forced to the left, the two clamping members 76 and 77 will rock about the pivot stud 75 in a clockwise direction and a short length of wire will be sheared by the cooperating action of the clamping member 77

and the upper surface of the semi-cylindrical guiding member 63. When the cam member 99 is thus actuated, the length of wire will be sheared off from the supply and will be transferred over to position above the guiding member 63 while the wire is still clamped between the clamping members 76 and 77. With the sheared-off length of wire thus positioned, the crank handle 175 may be rotated to actuate the lever 167, which will drive the die 152 downward sharply to form the end of the wire, as shown in Fig. 8. After the die 152 has thus operated on the end of the sheared-off length of wire, die members 153 and 154 may be brought into association with the sheared-off length of wire to perform their forming operations on the end of the wire. It should be noted that the die member 154 has a flat forming surface 183 on it so that in the final forming step, a flat head will be formed on the wire 15, thus to facilitate its attachment as a support and a conductive lead for the crystal.

What is claimed is:

1. An apparatus for forming articles from elongated material comprising a material guide adapted to form one element of a shear, a shearing and forming die including two complementary parts, a common pivotal mounting for said parts, means for normally positioning said die in alignment with said guide, means for slightly separating said parts in said normal position, means for moving said die about its pivot to shear the material, clamp it, and transfer it to a forming position, and means for forming the material in said latter position.

2. An apparatus for forming articles from elongated material comprising a material guide adapted to form one element of a shear, a shearing and forming die including two complementary parts, a common pivotal mounting for said parts, a spring-pressed plunger and an adjustable stop cooperating to normally position said die in alignment with said guide, a compression spring for slightly separating said parts in their normal position, means for feeding a length of material between said parts, means for gaging the length of material, a cam actuated plunger for closing said die parts and simultaneously moving said die about its pivot to shear the material and transfer it to a forming position, and cam operated reciprocable means for forming the material while being held in said latter position by said die.

3. An apparatus for forming articles from elongated material comprising a material guide adapted to form one element of a shear, a shearing and forming die including two complementary parts, a common pivotal mounting for said parts, a spring-pressed plunger and an adjustable stop cooperating to normally position said die in alignment with said guide, a compression spring for slightly separating said parts in their normal position, means for feeding a length of material between said parts, means for gaging the length of material, a cam actuated plunger for closing said die parts and simultaneously moving said die about its pivot to shear the material and transfer it to a forming position, a rotatable block carrying said gaging and forming means, and means for moving said block to carry the gaging and forming means in an arcuate path into direct alignment with the material to be formed.

4. An apparatus for forming articles from elongated material comprising a material guide including complementary parts having grooves facing each other for receiving the material, a

shearing and forming die comprising two complementary parts having grooves facing each other for receiving material fed through said guide, a pivotal mounting for said die, means for normally positioning said die in alignment with said guide, and means for causing said guide to grip the material and moving said die to shear the material.

5. An apparatus for forming articles from elongated material comprising a material guide including complementary parts having grooves facing each other for receiving the material, a shearing and forming die comprising two complementary parts having grooves facing each other for receiving material fed through said guide, a pivotal mounting for said die, a spring-pressed plunger and an adjustable stop cooperating to normally position said die in alignment with said guide, a compression spring for slightly separating said parts in their normal position, means for feeding a length of material through said guide into position between said die parts, means for gaging the length of material, means for simultaneously causing said guide to grip the material and moving said die to shear the material and transfer it to a forming position, and cam operated reciprocable means for forming the material while being held in said latter position by said die.

6. An apparatus for forming articles from elongated material comprising a material guide including complementary parts having grooves facing each other for receiving material fed through said guide, a pivotal mounting for said die, a spring-pressed plunger and an adjustable stop cooperating to normally position said die in alignment with said guide, a compression spring for slightly separating said parts in their normal position, means for feeding a length of material through said guide into position between said die parts, means for gaging the length of material, means for simultaneously causing said guide to grip the material and moving said die to shear the material and transfer it to a forming position, a rotatable block carrying said gaging and forming means, means for moving said block to carry said gaging and forming means in an arcuate path into direct alignment with the material to be formed, and means for locking said block against rotation.
